(21) Appl. No.: **29/268,709**

(57) **CLAIM**

(22) Filed: **Nov. 9, 2006**

The ornamental design for footwear upper, as shown and described.

(51) **LOC (8) Cl.** **02-04**

DESCRIPTION

(52) **U.S. Cl.** **D2/970**

FIG. 1 is a perspective view of the footwear upper, showing our new design;

(58) **Field of Classification Search** D2/970,

FIG. 2 is an enlarged top perspective view thereof;

D2/897, 901, 909, 910, 911, 912, 969, 972;

FIG. 3 is a reduced right side view thereof;

36/45, 7.1 R, 83, 114

FIG. 4 is a reduced left side view thereof;

See application file for complete search history.

FIG. 5 is an enlarged front view thereof; and,

FIG. 6 is an enlarged rear view thereof.

(56) **References Cited**

FIGS. 1–6 show features of an article of footwear in phantom lines. These features are shown for environmental purposes and do not form any part of the claimed design. Further, the phantom lines immediately adjacent the solid-line portions of the design form the boundary of the design, with the phantom lines forming no part of the claimed design.
